PLUG FOR ELECTRIC LIGHT FIXTURES

Filed Dec. 3, 1928

UNITED STATES PATENT OFFICE

HUBERT E. WAYLAND, OF SOUTH KNOXVILLE, TENNESSEE

PLUG FOR ELECTRIC-LIGHT FIXTURES

Application filed December 3, 1928. Serial No. 323,356.

This invention relates to a plug adapted to be screwed into a socket of an electric fixture.

An object of the invention is the provision of a plug which may be quickly inserted in the socket and requiring but a slight turn in the socket for fixing the plug in secure contact with the socket, while maintaining electrical conducting elements in proper relation.

Another object of the invention is the provision of a plug which may be readily inserted in a socket when given a slight rotation in one direction for securing the plug in operative relation in the socket while a slight turn in the opposite direction will free the plug from engagement with the socket.

This invention will be best understood from a consideration of the following detailed description, in view of the accompanying drawings forming a part of the specification; nevertheless it is to be understood that the invention is not confined to the disclosure, being susceptible of such changes and modifications which shall define no material departure from the salient features of the invention as expressed in the appended claims.

30 In the drawings:

Figure 1 is a view in elevation of a plug constructed in accordance with the principles of my invention.

Figure 2 is a vertical section of the plug shown in Figure 1.

Figure 3 is a horizontal section taken along the line 3-3 of Figure 2.

Figure 4 is a similar section showing the locking plate in an inoperative position,

40 Figure 5 is a fragmentary vertical section taken along the line 5-5 of Figure 6.

Figure 6 is a vertical section of a modified form of plug,

45 Figure 7 is a horizontal section of a modified form of plug taken along the line 7-7 of Figure 6.

Referring more particularly to the drawings, 10 designates a socket having an outer shell 11 of metal, an inner metal sleeve 12 and a cylinder 13 formed of insulating ma-

terial. The bottom 14 of the socket is likewise formed of insulating material and has a contact member 15 secured at 16 to the bottom 14. The screw shown at 16 is connected with one of the wires of the house current while the sleeve 12 is connected to the other terminal of the house current. The sleeve, as shown at 17, is provided with internal threads to engage the usual threads of a plug of well known make.

60 The plug which is constructed in accordance with the principles of my invention has a body member 20 which is solid and formed of insulating material. This body has a centrally disposed screw 21 threaded into a nut 22 which is imbedded in the body 20. The outer end of the screw has a head 23 which is adapted to engage a contact member 15 when the plug is in position. A flanged member or cap 24 formed of metal is located at the inner end of the plug and is adapted to be engaged by the head 23 of the screw 21.

65 An electric house wire 25 is inserted through a passage in the body 20 and is connected to the cap 24 or the bolt 21 in any approved manner.

70 A plate 30 is secured to one wall of a pocket 31 formed in the body member 20 and approximately at diametrically opposite points to the thread portions 32. A wire 33 is inserted through a passage 34 in the body 20 and is secured to the plate 30 and in electrical contact therewith by means of a screw 35. This plate at one end has perforated ears 36.

75 A plate or tongue 37 has laterally disposed lugs 38 adapted to be received by the perforated ears 36. It will be thus seen that the plate 37 is pivotally mounted on the plate 30 and thereby swingable on the lugs 38 within the pocket 31. A spring 39 has its opposite ends engaging respectively the plate 31 and the plate 37 and has a coil portion secured adjacent the lugs tending to move the plate 37 into engagement with the wall 40 of the pocket 31.

80 The outer end of the plate 37 is shaped to conform to a cross sectional area of a continuation of the mutilated threads 32 which normally would occur at points dia-

metrically opposite said threads. The outer end of the tongue therefore has a pair of projections 41 and 42 with a groove 43 lying between said projections. It will also be noted that the outer edges of the projections 41 and 42, as shown at 44, are rounded in order to facilitate the insertion or removal of the plug as will be presently described.

Referring more particularly to the modified form shown in Figures 6 and 7 it will be seen that the same socket 10 is employed in connection with the modified form of the plug having a body member 50 formed of insulating material. The body has an axially disposed screw 51 provided with a head 52 adapted to engage the contact 15. A clip 53 formed of metal is adapted to be engaged by the head 52. A head or screw is connected in any approved manner with an electric wire 25 which extends through a chamber 54 of the body 50.

A metal sleeve 55 is provided with threads 56 adapted to engage threads 17 of the socket 10. At points directly opposite the threads 56 the sleeve is free of threads, as indicated at 57, and is provided with a slot 58 directly opposite a pocket 59 and co-extensive with the outer end of the pocket.

A plate 60 is located within the pocket 59 and is provided with pintles 61 located within sockets in the body 50. A spring 62 has one end engaging the plate 60 and the other end, as shown at 63, engaging one wall 64 of the pocket 59. The plate 60 engages the opposite wall 64 of the pocket 65.

The outer free end of the plate 60 projects through the opening 58 and is shaped to conform to a section of the threads 56 so that when the plug is screwed into the body 50 the end of the plate will co-operate with the threads 56 which provides for the threading of the plug into the socket 10. A wire 66 is secured to a plate 67 which is in electrical contact with the sleeve 55. The wire 66 forms the other part of the circuit which may be extended to some electrical contrivance.

The operation of my device is as follows: In either case the plug is inserted within the socket 10 and due to the fact that the plates 37 or 60 are movable against the action of their respective springs, the plates will move inwardly of their respective pockets when the plug is forced into the socket. The insertion of the plug may be facilitated by a slight left hand turn of the plug. After the plug has been properly positioned the same is given a slight right hand turn whence the plug will be locked in position with the contact 23 or 52 engaging the spring contact member 15. When it is desired to remove the plug it is only necessary to give the plug but a slight turn whence the same may be withdrawn from the socket.

It will be noted by this construction that it

is not necessary to revolve the plug a number of times in order to secure the same in place since but a fractional turn of the plug is necessary after the same has been inserted in the socket, thereby avoiding the unnecessary twisting of the wires of the plug.

I claim:—

1. A plug having a body formed of insulating material, a portion of the body having thread portions, and a recess diametrically opposite the threads, a metal plate pivotally mounted in the recess, and eccentric to said body, and having the free end thereof normally projecting from the recess and the marginal portion of said free end shaped to conform to a cross section of the thread portions and a spring for urging the plate to said normally projecting position.

2. A plug having a body formed of insulating material, a portion of the body having thread portions, and a recess diametrically opposite the threads, a metal plate pivotally mounted in the recess, and eccentric to said body, and having the free end thereof normally projecting from the recess and the marginal portion of said free end shaped to conform to a cross section of the thread portions and a spring for urging the plate to said normally projecting position, the free end of the plate at the corners thereof being rounded to facilitate the insertion of the plug.

3. A plug having a body formed of insulating material, a portion of the body having thread portions, and a recess diametrically opposite the threads, a metal plate pivotally mounted in the recess, and eccentric to said body, and having the free end thereof normally projecting from the recess and the marginal portion of said free end shaped to conform to a cross section of the thread portions and a spring for urging the plate to said normally projecting position, a terminal in the inner end of the body, a wire connected with the terminal, and a wire connected with the plate.

4. A plug having a body formed of insulating material, a portion of the body having thread portions, and a recess diametrically opposite the threads, a metal plate pivotally mounted in the recess, and having the free end thereof normally projecting from the recess and the marginal portion of said free end shaped to conform to a cross section of the thread portions, and a spring for urging the plate to said normally projecting position, the plate being pivoted outwardly of the center so that the free end of the plate projects beyond the confines of the body in one position, while being disposed within the confines of the body in an opposite position.

HUBERT E. WAYLAND.
